UNITED STATES PATENT OFFICE.

ANDREW EINSFELD, OF SAN FRANCISCO, CALIFORNIA.

DUPLEX MOP.

1,271,870.

Specification of Letters Patent.

Patented July 9, 1918.

Application filed June 29, 1916. Serial No. 106,604.

To all whom it may concern:

Be it known that I, ANDREW EINSFELD, a citizen of the United States, and a resident of the city and county of San Francisco, State of California, have invented a new and useful Duplex Mop, of which the following is a specification.

My invention relates to mops and particularly to mops for oiling and polishing floors.

An object of my invention is to provide a mop holder and means for readily attaching the mop to or detaching it from the holder.

Another object of the invention is to provide an improved means for attaching a handle to the mop.

The invention possesses other features of advantage, some of which, with the foregoing, will be set forth in the following description of the preferred form of my invention, which is illustrated in the drawings accompanying and forming part of the specification. It is to be understood that I do not limit myself to the showing made by the said drawings and description, as I may adopt variations of the preferred form within the scope of my invention as set forth in the claim.

Figure 1 is a perspective view of the mop of my invention, a portion being broken away.

Fig. 2 is a view of the tightening or tension band.

In mops of the class described, it is a matter of great importance to be able to easily remove or attach the mop to the mophead. In the mop of my invention I contemplate the use of two mops with each mophead, one for applying the polish to the floor and one for rubbing the floor to a gloss. It is therefore one of the objects of my invention to provide a means for fastening the mops to the mophead which is easily and quickly operated and which is absolutely secure and tight so that the mophead can never be accidentally loosened.

The mop of my invention comprises a mophead 2 formed conveniently of sheet metal and having its outer edges bent downwardly and curved to provide a rather broad grooved edge 3 around the periphery of the mophead. Preferably the mophead is triangular in form so as to permit of its application in corners.

A mop 6 having an opening 7 lengthwise through its top edge 8 is adapted to encircle the mophead 2, the top edge 8 lying in the grooved edge 3 thereof. A band 9 is disposed in the opening 7 and surrounds the 60 mophead and by tightening or loosening the band 9, the mop is bound tightly in the grooves or detached therefrom.

Preferably the band 9 consists of wire links 12, 13 and 14 and the ends of the band 65 are connected together by the turnbuckle 15. The middle link 13 is preferably bent in the center to conform to the shape of the mophead and the end links 12 and 14 are preferably attached to the middle link by 70 means of eyes formed upon the ends of the links. Preferably the turnbuckle 15 is revolvably attached at one end to the link 12, and the other end of the turnbuckle is threaded to engage the threaded end of the 75 link 14. A portion 16 of the edge 3 of the mophead is removed and the turnbuckle is preferably of a size such that it extends closely adjacent this opening so that when loosening or tightening the turnbuckle, the 80 fingers may easily engage the periphery thereof on opposite sides. Preferably, also, the turnbuckle is provided with a hole 17 into which a nail or other small article may be inserted, so that, in need, a greater turning effort may be exerted upon the turnbuckle than would be possible by the fingers 85 alone.

The top of the mophead is formed to provide two wings or lugs 21 and pivotally 90 mounted upon these lugs by means of the screw 22 is a socket 23 for the handle 24 of the device. The socket 23 is formed of stiff wire in the form of a helix and the ends 25 are turned downwardly to form eyes through 95 which the screw 22 passes. A spacing block 26 is mounted on the screw 22 between the ends 25 of the socket 23. The spacing block serves to position the ends of the socket relative to the wings 21. The end of the 100 handle 24 is provided with threads 27 of the same pitch as the helical coil and is readily turned into or out of the socket formed by the coil.

In attaching the mop to the mophead, 105 the band 9 is passed through the opening 7 in the top edge of the mop and both together placed upon the mophead, the top edge of the mop and the band lying in the grooved edge 3. The turnbuckle 15 is then threaded 110

on the end of the link 14 and turned up tight, binding the mop securely on the edge of the mophead.

By providing two mops, each with its tension band, polish may be conveniently applied to the floor with one mop, then the mop changed and the floor rubbed to a gloss with the other mop. By merely unscrewing the turnbuckle 15 to loosen the tension band, the mop is easily slipped off of or on to the mop head. Means are thus provided wherewith the change from one mop to the other is effected with the minimum of time and effort.

15 I claim:

An article of manufacture, comprising a mop, a mop head having tabs cut from the

material thereof, and turned upwardly to form lugs thereon, a helical coil of wire having the ends formed into eyes adapted to lie 20 contiguous with said lugs, a block disposed between said eyes, a bolt passing through said lugs, eyes and block to pivotally secure the coil upon the lugs, means for securing the mop to the mop head and a handle provided with threads adapted to engage in said coil.

In testimony whereof, I have hereunto set my hand at San Francisco, California, this 3rd day of June, 1916.

ANDREW EINSFELD.
